UNITED STATES PATENT OFFICE.

KAROLA KNOBLOCH, OF BALTIMORE, MARYLAND.

DESIGN FOR A GRID FOR ELECTRIC STORAGE BATTERIES.

46,834.

Specification for Design.

Patented Jan. 5, 1915.

Application filed August 14, 1914. Serial No. 856,872. Term of patent 3½ years.

To all whom it may concern:

Be it known that I, KAROLA KNOBLOCH, a citizen of the United States, residing at Baltimore, Maryland, have invented a new, original, and ornamental Design for a Grid for Electric Storage Batteries, of which the following is a specification, reference being had to the accompanying drawing, forming part thereof.

The figure is a plan view of a grid for

electric storage batteries, showing my new design.

I claim:

The ornamental design for a grid for electric storage batteries, as shown.

KAROLA KNOBLOCH.

Witnesses:

H. FINLAY FRENCH,
Wm. T. HARLAND.
